(57) **CLAIM**

The ornamental design for a portal opener, as shown and described.

DESCRIPTION

FIG. 1 is a rear-right view of the portal opener showing my new design;

FIG. 2 is a rear elevational view thereof,

FIG. 3 is a right elevational view thereof,

FIG. 4 is a left elevational view thereof,

FIG. 5 is a front elevational view thereof,

FIG. 6 is a bottom plan view thereof; and,

FIG. 7 is a top plan view thereof.

The portions of the drawings shown in broken lines are for illustrative purposes only and form no part of the claimed design.

1 Claim, 3 Drawing Sheets

FIG. 1

FIG. 2
